UNITED STATES PATENT OFFICE.

FRANZ JOSEF FISCHER, OF DRESDEN, GERMANY.

CURRENT-CONVERTING MEANS.

Application filed April 20, 1922. Serial No. 555,754.

To all whom it may concern:

Be it known that I, FRANZ JOSEF FISCHER, a citizen of Germany, residing at Dresden, Germany, have invented certain new and 5 useful Improvements in Current-Converting Means, of which the following is a specification.

My invention refers to devices for converting electric currents and more especially 10 to a device operating in a manner similar to a transformer and designed mainly for very high voltages. The device according to the invention can be applied for instance for the purposes of measuring and testing high 15 current plants. It has the outward appearance of the well known normal high current ducts and can be arranged in a similar manner, but serves at the same time for converting a primary current into a secondary current or for inductively connecting two circuits which are not conductively connected, thus simultaneously serving as a duct or 20 leading-in and as a current converting means. It combines high efficiency when 25 used for converting and similar purposes with great security against puncture and is distinguished from devices of this kind as heretofore constructed by its outer coil being more easily wound and by the comparative 30 simplicity and low cost of manufacture of extensive and even very large size pieces of apparatus of the kind referred to.

The current converter according to the present invention substantially consists of a 35 bulb-like bottle shaped body made up, at least in its neck portion, of insulating material and the bulging portion of which is traversed by a passage or support of insulating material and upon the outer surface 40 of which one of the coils and preferably the primary coil is wound, while the second coil, preferably the secondary one, together with its iron core is suitably mounted on the interior thereof.

In the drawings affixed to this specification and forming part thereof a device embodying my invention is illustrated by way of example.

In the drawings—

Fig. 1 is a longitudinal section of a device 50 comprising a body consisting of insulating material throughout, the support or tubular passage spoken of above being shown in cross section.

Fig. 2 is another longitudinal section running the entire length of the support or tubular passage while

Fig. 3 is a cross section taken at about half the height of the support or tubular passage, the core of the inner coil being 60 shown in elevation.

Referring to the drawings, A is the bulb or bottle shaped bottomless body consisting of insulating material, preferably porcelain, throughout. The bulb or bulging portion 1 65 contains a support or tubular passage 2 integral therewith and consisting of the same material, said passage having the form of a tube of cornered cross section with rounded edges. The primary coil B is wound around 70 the tube 2, this being easily effected owing to the missing bottom. The conducting wire or coil ends b, b of the primary coil project through the neck portion 3 of the body A, the opening 4 of the neck portion 3 being 75 closed by a lid or cap 5.

Within the tubular passage 2 there is arranged the iron core C with the secondary coil D. 6 is an insulating tube carrying the 80 coil windings. Outside the body A the core C is surrounded and closed by a ring e, so as to constitute a kind of barrel-shaped core. The ends of the secondary winding are connected with the terminals 7.

Upon the body A which is provided with 85 annular grooves 8 above the support or tubular passage 2 an angularly flanged ring E is secured by being cemented thereon and to which the terminals 7 are insulatingly attached. A metallic container F constituting 90 a bottom closure for the body A is attached to the circular flange of ring E and is filled together with the support or tubular passage 2 with oil or with some suitable di-electric material capable of hardening after being 95 filled in.

Instead of designing the device as shown in the drawings I may however also provide a simple flat bottom of metal or of insulating material applied to the lower edge of the 100 body A so as to form a closure.

The cavity of the entire body may and should preferably be filled with oil or with some other liquid or solidifying or gaseous insulating material.

My invention is obviously not restricted to the modifications and forms of constructions herein shown and described but it is capable 105

of various other modifications and forms of embodiments, and it is susceptible of various changes and modifications in the relative arrangement of parts and connections to correspond to existing conditions of use, but without deviating from the spirit of my invention.

I claim:

1. In a device for converting electric currents in combination an annular horizontal core, comprising a shell and a diametrical transverse bar, a hollow body comprising a transverse tube adapted to receive said transverse bar, and a tank adapted to receive a dielectric surrounding said body and said

core and extending beyond the level of said transverse bar.

2. In a device for converting electric currents in combination an annular horizontal core, comprising a shell and a diametrical transverse bar, a hollow body comprising a transverse tube adapted to receive said transverse bar, a tank adapted to receive a dielectric surrounding said body and said core and extending beyond the level of said transverse bar and a shoulder on said tank adapted to support said core.

In testimony whereof I affix my signature.

FRANZ JOSEF FISCHER.
